CUTTING MACHINE

Albert P. Komow, Brooklyn, N. Y.

Application May 7, 1932. Serial No. 609,815

5 Claims. (Cl. 164—75)

This invention relates to cutting machines and in particular to a hand guided machine used in the cutting of cloth and other textile fabrics.

A particular object of my invention is to overcome objectionable features found in machines of the character referred to in present day use and to this end, I have provided a machine in which an improved system of lubrication is employed for the purpose of rendering silent the operation of the cross head and knife driven thereby. A further object is to provide a rod and regulating clamp therefor, through the medium of which the material engaging foot may be adjusted for various purposes, means being also provided for mounting on the machine a lamp socket and an electrical connector so that the two latter devices will not become loosened and the vibration will be eliminated particularly in the lamp so that the filament thereof will not be destroyed.

A still further object of my invention is the provision of a handle cast integral with a part of the motor housing, it having been found that in machines of this character the use of screws is objectionable in that the vibration loosens them and permits the parts to become separated.

Changes and variations may be made in the construction shown and described without departing from the principles of the invention or sacrificing its chief advantages; hence such invention is not to be confined to the structures shown in the accompanying drawings, in which;

Figure 1 is a view in side elevation of a cutting machine constructed in accordance with my invention, the presser foot rod and its regulating parts being illustrated, as well as other features of my invention.

Figure 2 is a view in front elevation showing the parts of the machine and illustrating how the presser foot rod is controlled in its vertical movement.

Figure 3 is an enlarged section taken on the lines 3—3 of Figure 2 illustrating the method of securing the clamp to the presser foot rod, and

Figure 4 is a fragmentary sectional elevation taken substantially on the line 4—4 of Figure 2 and illustrating the lubricating means employed in the reciprocating parts of the machine.

Figure 5 is a section taken on the line 5—5 of Figure 4 illustrating the method of oiling the slide surfaces of the cross head and the wrist pin bushing.

Referring to the drawings in detail, 5 indicates an exposed portion of a motor encased at its opposite ends in the rear housing 6 and at its

forward end in the front housing 7. The front housing 7 is provided with a depending portion 8 to which is secured a switch housing 9 and handle 10, the switch housing being provided with the usual starting switch button 11 which may be operated by the hand of the one guiding the machine. To this depending portion 8 is secured, the guide 12 through the medium of the bracket 13 which is secured directly to the depending portion 8 of the front housing 7 in any suitable manner, the guide 12 at its lower end is suitably secured in the base 14, the construction of which is well known and need not be described, it being sufficient to note that the base 14 is slotted where the guide 12 enters the same so that a reciprocating knife 15 operable in the guide 12 may pass downwardly into the base 14 so as to effectively cut material indicated by the dot and dash line 16 that is resting on the plate or rather, under which the plate or base 14 is passing, it being understood that the machine is guided by the operator who holds the handle and the reciprocations of the knife or cutting element 15 effectively cuts through the material.

The front housing 7 is further provided with a side projection 16 to which is secured the upstanding spring arm 17, the upper end of which is offset as at 18 and so positioned that an electric contact plug 19 may be forced downwardly into suitable contact sockets provided in the projection 16, passed the strip 17 which will yield during the passage of the plug 19, but when the plug 19 is in the final position, will assume a position whereby the upper portion 18 thereof will engage over the edge of the plug 19 and hold the same securely in position. This feature of my invention overcomes the objection heretofore present in that the vibrations of the machine during operation have a tendency to loosen the contact plug 19 so that it finally worked out of the sockets in which it was held and broke the circuit.

A spring strip 20 is also attached as at 21 to the projection 16 and supports at its outer end, the lamp socket 22, the wires from which are encased in the coil conduit 23 leading into the projection 16 to a suitable source of contact with the sockets in which the plug 19 is positioned. The strip 20 supporting the lamp is flexible and will take up the vibrations of the machine so that the filament of the lamp bulb will not become readily broken due to the constant vibration and the strip 20 having pivotal connection as at 21 with the projection 16, may be swung from side to side to throw the light at any desired point.

Referring to the lubricating feature of my invention, attention is directed particularly to Figure 4 where it will be noted that the front housing 7 is provided with an integral circular boss 24, recessed as at 25 to provide a seat for the ball bearing 26, through which passes the motor shaft 27 carrying at its outer end, the eccentric disk 28. To this eccentric disk is pivoted in any suitable manner, one end of the connecting rod 29, the lower end being pivoted through the medium of the pin 30 with a cross head 31 which, operating in the suitable cross head guides 32, causes reciprocation of the cutting knife 15 which is secured to the lower end of the cross head in any suitable manner, this connection not being shown as it is not deemed to be a part of my invention.

A cover 33 is provided for the front housing to cover the mechanism just described and at the top of this cover 33, I provide an oil cup 34 of the usual character, the opening 35 of the cover 33 in which the oil cup is disposed, being in alignment with a vertical bore 36 provided in the boss 24. This bore 36 passes vertically through the boss 24 and opens at one side into the seat or cut-out 25 provided for the reception of the ball bearing 26 with the result that this ball bearing 26 is lubricated and excess lubricating fluid flows down through the bore 36 and into a well 37 provided in the upper end of a protuberant portion 38 formed on the front housing 7 and adapted to act as a support for the cross head guides 32 which are secured thereto. This well 37 is provided with an outlet pipe 39 through which extends a wick 40, one end of which is coiled in the well 37 and the other of which depends from the mouth of the pipe 39 so that it seats in a chamber 41 provided in the upper end of the cross head 31 each time that the cross head reaches its highest position so that lubricating fluid accumulating on the depending end of the wick 40 is transferred to the chamber 41 on the cross head and flowing through the bore 42 of the hollow pin 30, lubricates the lower end of the connecting rod which is secured by the pin 30 to the cross head.

The pin 30 is provided with the transverse bores 75 which coincide with the transverse bores 76 in opposite sides of the cross head 31, these bores 76 being also connected by short bores 77 to the flat face of the cross head guide 32, the bores 76 opening into the bevelled faces of the cross head so that the sliding surfaces of the cross head are properly lubricated. The pin 30 is further perforated in its connecting rod holding portion so that the oil may be lead from the pin bore to an annular groove 78 on the outside of the pin 30.

The cover 33, as shown in Figure 1, is provided with the extended portion 43 through which the presser foot rod 44 has sliding movement, carrying at its lower end, the presser foot 45 which is bifurcated at one side to fit about the knife 15 and edges of the guide 12, an eye or opening 46 being provided in the presser foot 45 through which may be observed the point where the knife cuts the material. The rod 44 is serrated as at 47 along one side thereof and above the extension 43 has slidably secured thereto, the clamp 48. This clamp, as illustrated in Figure 3, consists of the thumb screw 49 which is threaded into the clamp 48 and has its inner end swaged over as at 50 so that its movement outwardly is limited, its movement inwardly causing the block 51, one face of which fits the contour of the rod

44, to frictionally engage the rod so that the clamp 48 is secured thereto in any adjusted position desired. The clamp is used for limiting the downward movement of the foot and one of its uses may be illustrated when the knife is sharpened and the foot has been previously set to a predetermined thickness of material. The rod 44 is pushed up so that the knife may be sharpened and when the rod is permitted to drop, the clamp having been previously secured in the proper position, will permit the foot to come to rest at the previous position without attention on the part of the operator. The clamp also permits movement of the rod so that the foot can follow the contour of the cloth or the surface thereof without causing the cloth to buckle or bulge in front of the foot as the machine is moved through the cloth in a cutting operation. The rod 44 is circular in cross section and due to this fact, the foot itself is self-centering and does not bind on the knife guide alongside of which the ends of the presser foot closely fit. In order that the rod 44 may be released or may be freed so that it may have vertical movement in either direction, use is made of a retaining member in the nature of a plunger 52, the outer end of which conforms to the shape of and closely fits against a cam 53. This cam, eccentrically mounted on the rod 54, and by means of spring 59, illustrated in Figure 1, serves to keep the plunger 52 in contact with the serrated surface 47 of the rod 44 against the action of the spring 55 positioned in a suitable receptacle formed in the projection 43 of the cover 33. The inner end of the plunger 52 is reduced in diameter to provide room for the operation of the spring and the end of the reduced portion 56 may be serrated to closely fit the serrations 47 of the rod 44.

The shaft or rod 54 upon which the cam 53 is mounted extends through the ears 57 formed integral with the cover 33. To one of these spaced ears 57 is secured one end 58 of a coil spring 59 positioned over the rod 54 and having its opposite ends 60 secured to a collar 61 which, through the medium of a set screw 62 is adjustably positioned on the shaft or rod 54. It is quite evident that by loosening the set screw 62, the collar 61 may be adjusted to vary the tension of the spring 59 so that the tendency of the cam to force the plunger 52 inwardly will be accomplished with greater force, if desired, and the rod 44 will be held securely in position. The end of the shaft 54 terminates in a curved handle portion 63 which lies adjacent the handle 10 of the machine so that it can be operated by the hand of the operator that engages the handle 10 and a movement of the handle 63 in the direction and to the position indicated in outline in Figure 2, will operate the cam 53 to permit the spring 55 to force the plunger 52 away from the rod 44 to release the same and permit free movement of the presser foot 45, if the same is resting on the cloth or permit raising or lowering movement thereof, it being understood that releasing of the handle 63 will immediately cause the rod 44 to be held in any adjusted position.

A further feature of my invention, as illustrated in Figures 1 and 2, is that the front housing is provided with an integrally formed handle 64 having the latterly extending finger pieces 65 through the medium of which the machine may be lifted.

In practice, it has been the custom to secure a separate handle to the motor housing by screws 150

but the constant vibration of the machine has loosened the screws and during the carrying of the machine, the handle has come off and permitted the machine to drop with the resulting damage to the machine itself and the person carrying the same.

It is evident, therefore, that I have provided features in connection with a cutting machine of the character referred to which facilitate its 10 operation, cut down the expense of operating and relieve the attendant of attention to a number of details, thus permitting him to turn out more work and pay more attention to the operation of the machine which must be closely attended to, to prevent spoilage of material.

My invention is not to be restricted to the precise details of construction shown since various changes and modifications may be made therein without departing from the scope of the invention 20 or sacrificing the advantages derived from its use.

What I claim is:—

1. The combination, in a machine of the character described, of a motor housing, a handle 25 extending therefrom, a presser foot, a rod serrated along one side and passing through said housing and carrying said presser foot at its lower end, a plunger normally in engagement with the serrations of said rod to maintain the rod in an 30 adjusted position, a revolvable cam for permitting disengagement of said plunger from said rod, a shaft for revolving said cam, and said shaft constituting a finger piece extending rearwardly to a point adjacent said handle.

35 2. The combination, in a machine of the character described, of a motor housing, a handle, a presser foot, a serrated rod passing through said housing and carrying said presser foot at its lower end, a plunger normally in engagement 40 with the serrations of said rod to maintain the rod in an adjusted position, a cam for permitting disengagement of said plunger from said rod, a shaft for operating the cam, said shaft constituting a finger piece extending rearwardly to a point 45 adjacent said handle, and a clamp adjustable on

said rod for limiting the movement thereof in one direction when said cam is operated.

3. The combination in a machine of the character described, of a motor, a housing therefor, a shaft passing through the housing, a boss on the housing constituting a journal for the shaft and having a vertical oil bore therein, a well integrally formed in the housing beneath, and in alignment with, said bore, a reciprocating cross head having a pocket in the upper surface thereof, a wick extending out of said well and having its end arranged to engage in said pocket at a point of travel of said cross head to transfer lubricating fluid from the well to the pocket, and 80 passages from the pocket to the slide faces of said cross head.

4. The combination in a machine of the character described, of a motor, a housing therefor, a shaft passing through the housing, a boss on the housing constituting a journal for the shaft and having a vertical oil bore therein, a well in the housing beneath, and in alignment with, said bore, a reciprocating cross head having a pocket in the upper face thereof, a wick extending out of said well and having its end arranged to engage said pocket at a point of travel 95 of said cross head to transfer lubricating fluid from the well to the pocket by momentary contact of the wick and pocket, passages from the pocket to the slide faces of said cross head, an eccentric rod, a bored pin for securing the eccentric rod to the cross head, and a passage from the cross head pocket to said pin bore for lubricating said eccentric rod.

5. The combination in a machine of the character described, of a motor housing, a handle formed integral with said housing, a rod, a presser foot carried by the rod, said rod having a serrated side and being round, whereby the 110 presser foot is self-aligning with a cutter, means for holding the rod in adjusted position including a spring, a cam and a plunger, means for 115 adjusting the tension on the spring, and a finger shaft for operating the cam extending rearwardly to a point adjacent said handle.
